[57] CLAIM

I claim the ornamental design of a peripheral hard drive device, as shown and described.

DESCRIPTION

FIG. 1 is a front perspective view of the peripheral hard drive device showing my new design;

FIG. 2 is a rear perspective view thereof;

FIG. 3 is a top view thereof;

FIG. 4 is a bottom view thereof;

FIG. 5 is a left side view thereof;

FIG. 6 is a front view thereof;

FIG. 7 is a rear view thereof; and,

FIG. 8 is a right side view thereof.
